JAMES W. SNEDEKER, OF ADRIAN, MICHIGAN, ASSIGNOR TO PAGE STEEL & WIRE COMPANY, A CORPORATION OF NEW JERSEY

CHAIN HOIST

Application filed July 20, 1926. Serial No. 123,607.

This invention relates to chain hoists, and has for its object the provision of a compact hoist, of a construction in which the principal operating parts are enclosed in such a manner as to avoid interference therewith by the chain, cable or other device utilized to operate the same or by the chain or cable customarily employed to sustain the load.

Another object of the invention is to provide a hoist structure which is exceptionally easy to operate, being provided with bearings designed to reduce the frictional coefficient to a minimum.

Still another object of the invention is to provide a hoist having parts which are individually easy to manufacture and are of an exceptionally durable nature, requiring few replacements, and not being subject to breakage.

Another object is to provide a hoist having a series of intermediate gears so arranged as to give a very powerful ratio of operation and at the same time adapted to permit ready changes of the speed ratio so that the hoist may be utilized in installations having different requirements.

The above objects and others are set forth and illustrated fully in the accompanying specification and drawings and are pointed out in the claims.

In the drawings,

Fig. 1 is a view in elevation of a chain hoist in the construction of which my improvements are embodied.

Fig. 2 is a similar view, on a larger scale, of the same with one side member removed.

Fig. 3 is a view in vertical section on the line III-III of Fig. 2.

In the illustrated embodiment, the parts designated by the reference numerals 1 and 2 are respectively the side members of a hoist, adapted for use as a chain hoist, or cable hoist, these side members being shown as disks, preferably of metal and spaced apart by suitable spacing members 3, to form a central chamber 4 adapted to receive the operating instrumentalities of the hoist, which are supported by the side members 1 and 2.

These members are designed to be con-

nected by suitable bolts 6, and suspended by means of a suitable device, such as the clevis 7.

The operating parts of the hoist, in pursuance of an important object of the invention, are preferably all contained between these side members or disks 1 and 2. In the now preferred embodiment, illustrated, I have shown a drum 8, adapted to rotate upon anti-friction bearings, such as the rolls 9 traveling upon inwardly projecting bosses 11 and 12 which extend toward each other from the side members 1 and 2 respectively. This drum is adapted to receive the cable or chain 13 which serves to support the load, a drop-sheave or pulley 15 being hooked at 16 to the load, the cable having a clevis 17 secured to the hoist and to which is attached one end of the operating cable or chain, the latter being formed into a bight 14, within which rests the drop-sheave, the other end of the cable being attached at 18 to the periphery of the drum, so that it may be wound up thereon between the radially projecting peripheries 19 of the disks 1 and 2.

For the purpose of operating the drum, I prefer to provide the same with an internal gear 20 secured to the drum in any suitable manner, or forming an integral part thereof, which is preferred for the sake of compactness, strength and durability, and this internal gear is caused to rotate by any suitable mechanism, the preferred form comprising a cross-shaft 21, having a driving gear 22, and also having a worm-gear 23 driven by a worm-shaft 24, the worm-shaft being provided preferably with a pulley 25 secured thereto outside of the disk, in position to receive an endless chain, cable, or other suitable actuating member operable manually in well-known fashion.

In pursuance of an important object of the invention I provide a series of intermediate gears connecting the driving gear 22 with the internal gear 20 and compactly disposed between the disks 1 and 2 so as to afford a very considerable reduction in the speed-ratio between the driving pulley 25 and drum 8, thus constituting the hoist a very powerful appliance, and I also ar-

range this intermediate gearing so that they are readily accessible upon removal of one of the side members, and can be easily removed, cleaned, or changed, their relative positions being such as to facilitate substitution of certain of the gears to effect changes of the speed ratio without interfering with the other gears of the series, thus adapting the hoist for use in the different kinds of service for which it may be utilized desirably.

For the above purpose I have provided a series of gears 31, 32, 33, 34, 35, 36 and two gears 37, all mounted preferably upon the disk 1, and arranged to be exposed by removal of the disk 2, the gears meshing with each other in their numerical order, the gear 31 being actuated by the gear 22 on the worm-shaft, and the gears 37 serving to drive the internal gear 20 and rotate the drum 8. Preferably two or more of the most accessible gears, as for example those occupying the positions indicated by the reference numerals 32 and 33, are adapted to serve as change-speed gears for which substitutions may be readily made, in well-known fashion, without disturbing other gears.

From the above description, it will readily be seen that the chain hoist forming the subject of this invention is powerful, compact, contains but few operating parts, and those protected by their enclosure within the side members of the hoist; the device is easily operated, having a low frictional coefficient by reason of the bearings; is not subject to breakage; and can be manufactured, assembled and operated at minimum cost of materials, labor and maintenance.

I claim:

1. A hoist of the class described, comprising side members connected together in spaced relation and a drum mounted rotatably on bearings carried by one of said members adjacent to its periphery, a series of gears mounted within the space enclosed by said drum and disks, one of said gears being connected with the drum, and a worm-shaft arranged to actuate another of the gears, said worm-shaft being mounted in bearings carried by one of the said members and adapted to be actuated by means outside of said hoist, including a pulley and a flexible endless member.
2. A hoist of the class described comprising side disks connected together in spaced relation and having their peripheries reduced to form circular bearing shoulders, a drum surrounding, and mounted rotatably on said bearing shoulders, the outer edges of said disks confining said drum laterally, but leaving the periphery of the drum free, a series of gears mounted within the space enclosed by said drum and disks, one of said gears being connected with the drum, and

a shaft arranged to actuate another of the gears, said shaft being mounted in bearings carried by one of the disks and adapted to be actuated by means outside of said disks.

3. A hoist of the class described, comprising side members connected together in spaced relation and a drum mounted rotatably on bearings carried by one of said disks adjacent to its periphery, a series of gears mounted within the space enclosed by said drum and disks, said series including an internal gear connected with the drum, and a worm-gear and worm-shaft arranged to actuate another of the gears, said worm-shaft being mounted in bearings carried by one of the disks and adapted to be actuated by means outside of said disks.

In testimony whereof, I have signed this specification.

JAMES W. SNEDEKER.
